UNITED STATES PATENT OFFICE.

EDWIN NORTON, OF PAGET WEST, BERMUDA, ASSIGNOR TO PERFECT VACUUM CANNING COMPANY, A CORPORATION OF MAINE.

VACUUM SEALING APPARATUS.

1,264,843.

Specification of Letters Patent. Patented Apr. 30, 1918.

Application filed February 12, 1914. Serial No. 318,373.

To all whom it may concern:

Be it known that I, EDWIN NORTON, a citizen of the United States, residing at Cedar Lodge, Paget West, Bermuda, have invented certain new and useful Improvements in Vacuum Sealing Apparatus, of which the following is a description, reference being had to the accompanying drawing and to the figures of reference marked thereon.

The invention relates to new and useful improvements in machines for closing cans or containers, and more particularly to machines wherein the air is exhausted from the containers prior to the final sealing of the same.

An object of the invention is to provide an apparatus or machine of the above character, wherein the cans or containers to be closed are presented to a vacuum creating chamber which is caused to engage only the upper end or cover of the can or container.

A further object of the invention is to provide a device of the above character with a tipping iron which operates to close the can or container prior to the releasing of the vacuum in the vacuum chamber.

A still further object of the invention is to provide means for automatically opening the vacuum chamber to the atmosphere after the can or container is closed, so as to permit the can or container to be separated from engagement with the vacuum chamber.

A further object of the invention is to provide means whereby the vacuum chamber is cut off from the vacuum forming apparatus except when a can to be closed is placed underneath the head carrying the vacuum chamber.

These and other objects will in part be obvious and will in part be hereinafter more fully described.

In the drawings which show by way of illustration one embodiment of the invention,—

Figure 1 is a plan view, with the parts broken away, showing a machine embodying my invention.

Fig. 2 is a perspective view of the essential operating parts of the same.

Fig. 3 is an end view, showing the frame and more or less diagrammatically certain of the parts of the machine.

Fig. 4 is an enlarged detail, showing the

train of mechanism for raising and lowering the closing heads and for controlling the vacuum pipe which is connected with the various vacuum chambers on the several heads.

Fig. 5 is a transverse sectional view through the machine and through one of the closing heads.

Fig. 6 is an enlarged detail showing in section one of the closing heads and also in section the valve for controlling the vacuum chamber.

Fig. 7 is an enlarged vertical section, showing a portion of the closing head in contact with a can body to be closed.

Fig. 8 is a similar view, showing the can body closed and the closing head raised therefrom.

Fig. 9 is a sectional view, showing a slightly modified form of the solder applying means.

The invention consists generally in providing a closing machine for closing cans which are put under vacuum, and consists of a closing head which has a movement relative to the can to be closed. This closing head is provided with a casing forming a vacuum chamber which is adapted to contact only with the cover or upper end of the can. The lower end of the chamber is formed with an elastic bell-shaped member, whereby the atmospheric pressure on the outer surface of said bell-shaped member assists in maintaining a perfect joint between said member and the can end.

The device further consists of mechanism wherein the chamber is placed under a vacuum after it is connected with the can or container, and this mechanism includes automatically operating devices which cut off the vacuum before the vacuum chamber is moved out of contact with the can end. The tipping iron extends through this vacuum chamber and is so operated as to close an aperture in the can end through which the can is placed under vacuum. Devices are also preferably provided for preventing the opening of the vacuum chamber to the vacuum creating device unless there is a can or container in engagement with the vacuum chamber. This feature is of especial advantage in a gang machine.

Referring more in detail to the drawings, I have shown the invention as applied to

what is known in the trade as the "Hawkins" type" of can closing machine. This type of machine is illustrated in the patent granted to M. J. Hawkins October 6th, 1896, No. 568,849. The main similarity between my present machine and this type of machine shown in the Hawkins patent is in the feed table and the means for presenting the cans to the closing devices. This feed table and 10 feeding means will, therefore, be referred to only in a general way in the present description.

The machine consists of a main supporting frame 1, which carries a table 2. The 15 table 2 is formed with an extension 3, and an endless conveyer 4, having spacing fingers 5, operates to slide the cans to be closed along the table and the extension 3. This endless conveyer runs over suitable sprocket 20 wheels 6 and 7 mounted in bearings in the table and operated through intermediate gearing by a gear wheel 8, carried by a shaft 9, which is operated by a belt wheel 10. The machine includes a plurality or a 25 gang of closing heads which are indicated in a general way by the reference numeral 11. The cans to be closed are placed on the table 2 between the retaining fingers 5 on the endless conveyer 4 and are moved 30 along in the direction of the arrow indicated in Fig. 1 and are finally brought to a position in front of the gang closing machine. As herein shown, there are twelve closing heads. When the conveyer reaches 35 a point so as to properly position twelve cans for closing, a feed slide 12, consisting of upper and lower members, see Fig. 5, is moved against the twelve cans simultaneously and these are slid underneath the closing heads. The upper and lower members of this feed slide are connected to rollers 13, which extend through the work support and engage switch cams 14. The feed 40 slides are moved along the switch cams by a rock arm 15, which is pivoted at 16 to the work table and is oscillated by a disk 17 carrying a crank pin 18, running in a cam slot 19 in the arm. This disk 17 is rotated from the main shaft 9 beneath the work 45 table. This mechanism moves the feed slide forward with the cams underneath the closing head and a continuous movement of the disk 17, through the coöperation of the switch cams, retracts the feed slides in a 50 manner fully described in said patent.

After the cans are closed they are removed from underneath the closing heads by reciprocating fingers 20. There is a finger for each closing head and these fingers work 60 through slides 21 in the work table. The fingers are carried by a bar 22, which is attached to a rod 23, the latter being adapted to slide in suitable bearings 24 and 25. Said rod is attached to an oscillating lever 26 which is rocked upon the main shaft. The

forward end of the rod 23 is provided with a roller 27, which coöperates with a switch cam 28, and as the rod moves toward the rear of the machine, or in the direction of the arrow shown in Fig. 5, the roller 27 70 will pass up onto the switch cam and thus raise the fingers through the slides in the table, so that they are brought into engagement with the cans, and a movement of these fingers toward the rear of the machine 75 will slide the cans from underneath the closing heads. The roller 27 passes off the end of the switch cam and pulls underneath said switch cam, so that the fingers are not raised above the table on their return stroke. Suitable guides 29 are provided for spacing the cans and holding the same in proper relation to the closing heads. When the cans are removed from underneath the closing heads they are brought into position to be 80 engaged by the endless conveyer 30, which is provided with spacing fingers 31. This endless conveyer runs from suitable sprocket wheels which are driven by beveled gear wheels 32 connected to a beveled gear wheel 90 33 on the shaft 9.

The main frame 1 is provided with standards 34 at each end and these standards are connected by a cross-bar 35, which has a downwardly projecting supporting plate 36. 95 The closing heads, as above stated, are twelve in number, as herein illustrated. It is understood, however, that this number of closing heads may be increased or decreased and from certain aspects of the invention a single closing head may be used. A description of one of these closing heads will answer for the others as they are each similar in construction. Each closing head, as shown in Figs. 5 to 8 inclusive, consists of a supporting rod or stem 37. This rod or stem is mounted to slide in the cross-bar 35. The rod or stem 37 carries a sleeve 38 at its lower end, and this sleeve is mounted to slide in the supporting plate 36. The sleeve 38 is 100 formed with a section 39 which fits the stem or rod 37. A threaded collar 40 screws into the upper end of the sleeve and forms an air-tight joint between the sleeve and the rod. The rod is also formed with an enlarged section 41, which provides a shoulder 42 on which the section 39 of the sleeve rests. A spring 43 bears against the upper end of the collar 40 and also engages a collar 44 fixed to the rod 37. This spring normally tends to 105 separate the collar 44 and the collar 40 and thus pulls the shoulder 42 yieldingly into contact with the section 39 of the sleeve. 115

The lower end of the rod 37 is formed into a tipping iron 45 which is preferably electrically heated. This tipping iron is for the purpose of closing the aperture in the can or container through which the air is exhausted from the can. The sleeve 38 below the section 39 forms a vacuum chamber. 120 125 130

A glass or porcelain extension 46 is clamped to the lower end of the sleeve by a surrounding cage 47. Said extension 46 has a shoulder 48 against the lower face of which rests an elastic bell-shaped mouth piece 49. This bell-shaped mouth piece and the porcelain extension are clamped between sections of the cage 47, as clearly shown in Figs. 7, 8 and 9 of the drawings, and the cage has a threaded connection 51 at its upper end with the sleeve 38. The cage has outwardly extending parts 52 which are adapted to engage the upper end of the can body and limit the downward movement of the sleeve when the rod or stem 34 is moved downward to bring the closing head into contact with the cover or can end. The bell-shaped mouth piece of elastic material projects below this cage and will first engage the cover so that the downward movement of the closing head presses said elastic bell-shaped mouth piece tightly into contact with the cover or end of the can. This tapered or bell-shaped elastic mouth piece will be held firmly into contact with the cover or end not only by the downward pressure of the closing head, but also by the atmospheric pressure on the outer thin edge when the chamber is placed into vacuum.

The sleeve 38 is provided with a port 53 through which the air is exhausted from the vacuum chamber and from the can or container. This port is connected with a short rigid pipe 54 in which is located a valve controlled by an arm 55. The arm 55 is connected with a rod 56 which slides in a bracket arm 57 attached to the sleeve 38. A spring 58 surrounds this rod 56 bearing at one end against the bracket 57 and at the other end against a collar 59 fixed to the rod. The rod also slides through a suitable bearing 60 in the cage 47 and extends beneath the lower face of the cage. When the closing head is raised from contact with the can body, as shown in Figs. 6 and 8; the spring 58 throws the rod to its extreme lower position, which closes the valve controlled by the arm 55. When the closing head is moved down onto a can, the rod 56 will engage the end of the can, as clearly shown in Fig. 7, and the raising of the rod will swing the arm 55 so as to open the valve controlled thereby and thus connect the vacuum chamber with the vacuum creating means.

There is a flexible pipe 61 which connects each closing head with a cross-pipe 62, see Fig. 1. This cross pipe 62 is fixed to the frame and is connected with a valve casing 63, in which is located a three-way valve 64.

The valve casing 63 is connected to a pipe 65 and to a suitable vacuum creating pump. The valve 64 is formed with ports 66, 67 and 68, all of which are connected together. When the parts are positioned, as shown in Fig. 6, the flexible pipe 61 will be directly

connected with the vacuum creating means. An oscillation of the valve 64, so as to bring the port 66 into connection with the flexible pipe 61, will also bring the port 67 into connection with a port 69 in the valve casing 70 which leads to the atmosphere. This turning of the valve also moves the port 68 out of register with the pipe 65, and the result of this manipulation of the valve is to cut off the flexible pipes from their connection with the vacuum creating means and also to connect each flexible pipe through the port 69 with the atmosphere.

The valve 64 has an arm 70 which is attached thereto for oscillating the valve. This arm is connected to a rod 71 which is guided by a bracket arm 72. The lower end of the rod 71 carries a roller 73 which runs in a cam groove 74 formed in the side face of the gear wheel 75. This gear wheel 75 in turn meshes with a gear wheel 76, which likewise meshes with a gear wheel 77 connected to an auxiliary shaft, which may be operated by belt wheels 78, or other suitable driving connections.

The closing heads are moved up and down by a cross-head 79 which is mounted at each end on a rod 80, which slides in suitable bearings 81 carried by the end standards. These rods are provided with suitable rollers 82 which coöperate with a cam-groove 83 in gear wheels 84 mounted at the respective ends of the main frame. The gear wheels 84 mesh with the gear wheels 77. Each of the rods or stems of the closing head are provided with a sleeve 85 which is journaled in the cross-head 79. Each sleeve is also provided with a gear wheel 86 and these gear wheels intermesh. The gear wheel 86 at one end of the closing head meshes with a driving gear 87, carried by a vertical shaft 88, which is rotated by a beveled gear 89 connected to a beveled gear 90 on the shaft 9. This gear wheel 86 meshing with the driving gear 87 slides thereon in the well-known manner. Through this connection each rod or stem 37 is rotated which gives a rotating movement to the tipping iron. It is obvious, however, that this rotating movement of the tipping iron may be dispensed with, if desired, and the tipping iron merely reciprocated longitudinally.

The sleeve 85 has a passage centrally located therein, through which an insulated wire 91 passes for making the proper electrical connections for heating the tipping iron. The other terminal of the electrical connection may be grounded through the machine. This wire 91 is connected with a contact washer 92, which has face contact with a washer 93. The washer 93 is connected by a wire 94 with a suitable source of electric current and this washer 93 is held from rotation in any suitable way. A collar 94' clamped to the sleeve 85 supports the

rod or stem in the cross-head. As the cross-head 79 reciprocates, all of the closing heads will be simultaneously raised and lowered therewith. In order to counterbalance to a certain extent the weight of the closing heads, the springs 95 may be provided which are placed between the cross-head 79 and the upper bearing 81 for the supporting rods 80.

The operation of my device is as follows:

10 A series of cans, indicated as A, are placed underneath the cross-heads, as shown in Fig. 2 of the drawings. In this figure, a second series of cans B are ready to be moved under the closing heads as soon as 15 the cans underneath the closing heads have been closed and removed therefrom. In this figure of the drawings, I have also shown a third series of cans C which have been closed and are moved onto the conveyer for 20 carrying the same away from the closing heads. When the cans are placed underneath the closing heads, each head is in the position shown in Figs. 6 and 8, that is, with the cross head 79 raised. The operating 25 cam groove 83 is formed with a concentric portion which holds the cross-head raised a considerable time so as to permit the cans to be fed underneath the closing heads. The gear wheel 84, having the cam groove there- 30 in rotates in the direction of the arrow in Fig. 4, and this will rotate the gear wheel 75 in the opposite direction, that is, in a clockwise direction, as viewed in this figure. After the cans have been placed under the 35 heads the cross head is lowered by the eccentric part of the groove 83 and as the cross-heads are lowered the rods or stems 37 are moved downward in their bearings. The first downward movement of each closing 40 head causes the rod 56 to engage the can end. If there is only one under the closing head it raises the rod and opens the valve controlled by the arm 55. The valve 64 is at this time closed. A further downward 45 movement of the closing head brings the elastic bell-shaped mouth piece into contact with the cover or end of the can and as the closing head continues its downward movement this elastic member will be pressed firmly against the cover or can end. As soon 50 as the downwardly projecting parts 52 of the cage 47 engage the cover or can end, the downward movement of the sleeve 38 ceases and the spring 43 will be compressed per- 55 mitting a further downward movement of the rod or stem 37, which forms the tipping iron. As soon as this downward movement of the sleeve 38 ceases, the cam groove 74 controlling the valve 64 opens the valve to 60 the vacuum creating means and the vacuum chamber of the closing head is at once put under vacuum exhausting the air from the can through the aperture *a* in the can A. After the air is exhausted from the can the 65 tipping iron 45 is moved into the aperture.

The aperture *a* is provided with a solder disk *d* which is at once melted by the iron and as the iron is preferably given a slight rotation, the solder will be caused to close the aperture. As the cross-head 79 is raised 70 the tipping iron is moved out of contact with the solder and the cam 74 is so shaped as to oscillate the valve 64, shut off the vacuum creating means and open the vacuum chamber to the atmosphere, so that the closing head may be freely raised from contact with the cover or can end. Otherwise, the raising of the closing head would lift the can. A further upward movement of the cross-head will raise the closing head from 80 contact with the can and permit the same to be discharged from the machine by the mechanism above described. If there is no can placed under any one of the closing heads, then the rods 56 will not be raised 85 and the pipe 61 will be closed to the vacuum chamber, so that the opening of the pipe 61 to the vacuum creating means will not decrease or destroy the vacuum in the other closing heads. 90

In Fig. 9 of the drawings, I have shown a modified form of solder applying means. Instead of placing solder in the form of a disk which is attached to the cover or can end, I may provide the wall of the vacuum 95 chamber with a tube 96 which extends to a point adjacent the lower end of the tipping iron and a solder wire 97 may be fed through this tube in any suitable way so as to position the solder in the path of the tipping iron, whereby a portion of solder will be melted by the tipping iron and caused to fill the aperture in the can or container. A suitable packing disk 98 may be provided for forming an air tight joint with the solder 100 wire, so as not to interfere with the placing of the vacuum chamber under proper 105 vacuum.

The can indicated at A in the drawings, Figs. 7 and 8, is of the type wherein a disk *c*, having an aperture or apertures therein, protects the vent hole in the cover or can end through which the air is exhausted. One type of can end of this character is shown and described in my prior Patent No. 115 933,103, granted September 7th, 1909.

While I have described a machine or apparatus wherein a number of closing heads are operated simultaneously, it will be understood that the invention from certain aspects thereof may be equally applied to a machine wherein the closing heads are operated one after another, or in a continuously operating machine instead of an intermittently operating machine. 120

It will also be obvious that minor changes in the details of construction and arrangement of parts may be made without departing from the spirit of the invention as set forth in the appended claims. 130

Having thus described my invention, what I claim as new and desire to secure by Letters Patent, is:

1. A vacuum sealing apparatus comprising a support for apertured containers, and a closing head adapted to be moved relative to said support, said closing head including a vacuum chamber adapted to engage the end of the container about the aperture, devices for placing said vacuum chamber under vacuum for exhausting the air from the container, a tipping iron located in said vacuum chamber for closing the aperture, and means for moving said vacuum chamber into and out of contact with the end of the container, said means including devices whereby the tipping iron is caused to close the aperture while said vacuum chamber is in contact with the end of the container. 55
2. A vacuum sealing apparatus comprising a support for apertured containers, and a closing head adapted to be moved relative to said support, said closing head including a vacuum chamber adapted to engage the end of the container about the aperture, devices for placing said vacuum chamber under vacuum for exhausting the air from the container, a tipping iron located in said vacuum chamber for closing the aperture, and means for moving said vacuum chamber into and out of contact with the end of the container, said means including devices whereby the tipping iron is caused to close the aperture while said vacuum chamber is in contact with the end of the container, 60
3. A vacuum sealing apparatus comprising a support for apertured containers, and a closing head adapted to be moved relative to said support, said closing head including a reciprocating rod, a tipping iron carried thereby, a sleeve mounted on said rod and having a vacuum chamber at its lower end, a spring for normally forcing said sleeve downwardly on said rod, a shoulder on the rod for limiting the downward movement of the sleeve, and means for moving said rod toward and from the container, whereby 65 said sleeve is caused to engage the container about said aperture prior to the engagement of the aperture by the tipping iron, means for placing said chamber under vacuum and for opening said chamber to the atmosphere 70 previous to the moving of the vacuum chamber out of contact with the end of the container and after the aperture has been closed by the tipping iron. 75
4. A vacuum sealing apparatus, comprising a support for apertured containers, a plurality of closing heads adapted to be moved relative to said support, each of said closing heads including a vacuum chamber 80 adapted to engage the end of the container about said aperture, means common to the vacuum chambers for placing the same under vacuum, devices for normally closing the passage leading from the vacuum creating means to each vacuum chamber, said devices including means operated by the containers for opening said passages. 85
5. A vacuum sealing apparatus, comprising a support for apertured containers and a closing head adapted to be moved relative to said support, said closing head including a vacuum chamber, a tipping iron located in said vacuum chamber for closing the aperture, and means for moving said vacuum chamber into and out of contact with the end of the container, said means including devices whereby the tipping iron is caused to close the aperture while said vacuum chamber is in contact with the end of the container, 90

In testimony whereof, I affix my signature, in the presence of two witnesses.

EDWIN NORTON.
